UNITED STATES PATENT OFFICE.

EDWARD W. NEWELL, OF PITTSBURGH, PENNSYLVANIA, ASSIGNOR TO THE
WESTINGHOUSE AIR BRAKE COMPANY, OF WILMERDING, PENNSYLVANIA, A
CORPORATION OF PENNSYLVANIA.

PERCUSSION-FUSE.

1,309,769.

Specification of Letters Patent. Patented July 15, 1919.

Application filed March 3, 1917. Serial No. 152,223.

To all whom it may concern:

Be it known that I, EDWARD W. NEWELL, a citizen of the United States, residing at Pittsburgh, in the county of Allegheny and State of Pennsylvania, have invented new and useful Improvements in Percussion-Fuses, of which the following is a specification.

This invention relates to projectiles, and more particularly to a percussion fuse therefor.

The principal object of my invention is to provide a percussion fuse mechanism of simple construction, which is positive and reliable in action, and which is adapted to be cheaply manufactured.

In the accompanying drawing; Figure 1 is a central sectional view of a projectile, showing my improved fuse mechanism applied thereto, the parts being shown in normal position; Fig. 2 a similar view, showing the parts in position just after impact; and Fig. 3 a detail view of the spring release ring.

According to the construction shown in the drawing, there is screwed into the nose end of the projectile body portion 1, a cylindrical casing 2 provided at its rear end with a primer 3. Adjacent to the primer 3, a plug 4 is screwed into the casing having a longitudinal bore for the reception of a firing plunger 5.

A closely wound spring 6 is secured at one end to the plug 4 and has its other end secured to a block 7 which is loosely mounted on an enlarged portion 8 of the firing plunger 5 and is adapted to engage a collar 9 carried by said plunger.

The outer end of the enlarged portion 8 of the plunger 5 is provided with an annular groove 10 within which is mounted a spring ring 11 which normally engages the outer end of a cylindrical inertia member 12.

The bore 13 of the ring 11 is such that when the ring is unrestrained, the same can be passed over the end of the portion 8 and is provided with an opening 14 to permit compression of the ring.

The nose 15 of the projectile is provided with a rearwardly extending cylindrical section 16 having the rear end chamfered.

In assembling the parts, the plug 4 is screwed into the casing 2 with the firing plunger 5 mounted in position, the inertia

member 12 is then placed in position, and the spring ring 11 is mounted in the groove 10. The nose 15 is now screwed into the casing 2 and as the nose is screwed in, the chamfered end thereof engages the ring 11 so as to collapse the same to the position shown in Fig. 1. After the fuse members are assembled, the casing 2 is screwed into the body portion 1 of the projectile.

When the fired projectile strikes, the inertia of the member 12 causes its forward movement, carrying with it the spring ring 11, which in turn pulls out the firing plunger 5 and stretches the spring 6.

The ring 11 is finally pushed out into an enlarged bore 17 of the nose 15 where the ring is free to expand, so as to release the firing plunger 5, as shown in Fig. 2. The plunger is then thrown rearwardly by the action of the stretched spring 6 and hits the primer 3 to explode the projectile.

It will be noted that in the normal position shown in Fig. 1, the firing plunger is held away from the primer 3 by the ring 11 engaging the groove 10, but when the plunger is released after firing, the same will be free to move rearwardly after the spring has returned to its normal position, so as to hit the primer 3.

The spring 6 may be placed under a slight initial stretch by making the inertia member 12 of such length that when the parts are assembled said member will press the ring 11 outwardly, thus slightly pulling out the plunger 5 and thereby stretching the spring. By placing the spring under an initial stretch, the parts will be prevented from rattling when in normal position.

The above described fuse construction is well adapted for use in connection with torpedoes, since the same is water tight.

Having now described my invention, what I claim as new and desire to secure by Letters Patent, is:

1. A fuse mechanism comprising a firing plunger, a spring acting on said plunger, a collapsible ring normally engaging said plunger, and a member operated by inertia upon impact of the projectile for moving said ring and plunger and thereby stretching the spring.

2. A fuse mechanism comprising a firing plunger, a spring acting on said plunger, a collapsible ring normally engaging said

plunger, a member operated by inertia upon impact of the projectile for moving said ring and plunger and thereby stretching the spring, and means for permitting the expansion of the ring during its movement to thereby release the plunger.

3. In a fuse mechanism, the combination with a firing plunger, of a casing, a spring secured to said casing and operatively connected to said plunger, a spring ring nor-

mally collapsed into a groove in the plunger, a member engaging said ring and movable by inertia upon impact of the projectile for moving said ring to first stretch the spring and then permit the release of the ring and 15 the retraction of the plunger.

In testimony whereof I hereunto set my hand.

EDWARD W. NEWELL.
